UNITED STATES PATENT OFFICE

WILBUR H. ARMACOST, OF NEW YORK, N. Y., ASSIGNOR TO THE SUPERHEATER COMPANY, OF NEW YORK, N. Y.

BOILER AND SUPPORTING MEANS FOR USE THEREWITH

Application filed July 13, 1931. Serial No. 550,496.

This invention relates to means for supporting superheaters in boilers and aims to provide an arrangement which shall be economical to manufacture and convenient to 5 install.

In the majority of straight-tube horizontal boilers of the water tube type, the generating tubes are arranged in horizontal rows but they are staggered in the vertical direction to compel the gases to pursue a tortuous path through the tube banks. Difficulties are encountered in boilers having such arrangement of the tubes in connection with the problem of suspending a superheater 15 from the generating tubes.

It is an object of my invention to provide satisfactory means whereby objects such as superheater elements and headers may be suspended from the generating tubes in tube 20 banks having tubes staggered.

The novel features of my invention are pointed out in the appended claims. The invention itself, however, together with its objects and advantages, will best be understood 25 from the following detailed description, taken in connection with the accompanying drawing, of a particular boiler having a superheater suspending means therein which is an illustrative embodiment of my invention.

30 In the drawing:

Fig. 1 is a lateral elevation of portions of the upper slag screen and tube banks of a water tube boiler of the straight horizontally inclined tube type having a superheater in 35 the space between the two tube banks and suspended from the upper bank.

Fig. 2 is a sectional fragmentary view on an enlarged scale of a portion of Fig. 1, taken on the line 2-2 of Fig. 4.

40 Fig. 3 is a fragmentary plan view taken on the line 3-3 of Fig. 4.

Fig. 4 is a fragmentary sectional elevation taken at right angles to Fig. 1.

Referring to the drawing in detail, 10 is 45 a boiler having an upper tube bank of generating tubes 12, 12. The arrangement of the tubes 12 is illustrated in detail in Fig. 4. Such arrangement is a common one and involves placing tubes 12 in horizontal rows 50 so arranged as to provide horizontal lanes

between the adjacent rows, but having the tubes in one horizontal row covering the spaces between the tubes in adjacent horizontal rows so that the tubes are staggered in the vertical direction, the spacing of the 55 tubes, moreover, being such that there are no clear vertical lanes through the bank although there are horizontal lanes through the tubes and two sets of inclined lanes through the tubes running at about 30 degrees to the 60 vertical and inclined in opposite directions.

In accordance with prevailing practice it becomes necessary in many cases to place a superheater in the space between the two 65 banks, and in this case to support at least part of the superheater from the boiler tubes. The upper bank is the more convenient one for this purpose, and at times all the weight to be so supported has been hung from its 70 bottom row. This is often an undesirably large load for such a single row, but on account of the difficulty involved in doing anything else the load is nevertheless often supported in this manner. By my invention I 75 provide ready means for distributing the load over several rows of tubes even when the tubes are relatively staggered as described.

My supporting means comprise thin elongated members 14 which are thin enough to 80 slide in between adjacent horizontal rows of tubes 12 and which are elongated sufficiently to span as many of the tubes 12 of the given row as necessary in the direction transverse to the length of the tubes. The members 14 resting on the tops of tubes 12 may be 85 connected to an object to be suspended from the tubes by members lying in inclined lanes through the tube bank. As illustrated, the object to be suspended from the tubes 12 is 90 a superheater having elements similar to the one illustrated at 15 in Fig. 1, the individual elements of the superheater being attached to transverse beams 16 by suitable 95 means which form no part of the present invention. In the arrangement illustrated, the beams 16 are suspended from the members 14 by means of hook members 18, 18. Preferably the hook members 18 are arranged 100 in pairs, a given pair 18 lying in oppositely

inclined lanes in the tube bank, the lower ends of the given pair of hook members 18 being brought approximately together and pinned by pivot pins 22, 22 to a common pair of lugs 20, 20 on the upper face of a beam 16. The upper ends of the hook members 18 engage the members 14 and in order to facilitate the assemblage of the hooks on members 14, I prefer to make the members 14 in the form shown and having connecting rods 24, 24 the ends of which are integral with saddle-like bearing members 26, 26 adapted to rest on the tops of the tubes 12. As appears clear in Fig. 2, the rod members 24 are of a size and shape such that the hook portions 18' of the upper ends of the members 18 can be easily slipped over rods 24. In order to distribute the weight on members 14 over the upper surfaces of tubes 12, the bearing members 24 preferably are made saddle shaped having cylindrical grooves in their lower faces of the same curvature as the outer surfaces of the tubes 12 so that each member 26 of a given member 14 has an extended bearing on one of the tubes 12. The tubes 12 are somewhat inclined to the horizontal to promote the thermal circulation of the boiler and, in order to prevent the hook members 18 and supports 14 from sliding downwardly on tubes 12, I prefer to provide collars 28 one of which can be clamped around one of the tubes 12 between the lower ends of a pair of hook members 18, each collar 28 having projections 28' adapted to contact with the members 18 so as to prevent their moving longitudinally of the tubes.

In the form of my invention illustrated in the drawing, there are four members 14, 40 the lowest resting on the lowest row of boiler tubes, and the others on successively higher rows. Preferably the two lowest rows, where the temperature is highest, have their members arranged nearest the headers of the boiler.

It will be seen an arrangement in accordance with my invention can be assembled in a boiler and moved therefrom quickly and conveniently and that it is economical to manufacture and install. The arrangement distributes the weight of a superheater or like object over a number of horizontal rows of boiler tubes. The arrangement generally, as well as its details, can obviously be varied considerably without losing the advantages or departing from the real spirit of the invention.

What I claim is:

1. The combination with a bank of generating boiler tubes having the tubes staggered in the vertical direction of a plurality of supporting members each supported on a different horizontal row of tubes in said bank and suspension members adapted to occupy 60 inclined lanes in said bank and to connect

an object to be supported below said bank to said supporting members.

2. The combination as set out in claim 1 and in which the lower supporting members are nearer the ends of the generating tubes. 70

3. The combination with a bank of generating boiler tubes having the tubes staggered in the vertical direction, of a plurality of supporting members each supported on a different horizontal row of tubes in said 75 bank, and suspension members adapted to connect an object below said bank to said supporting members.

4. The combination with a bank of generating boiler tubes having tubes staggered in a vertical direction, of a plurality of horizontal supporting members arranged transversely on the tubes of said bank, suspension members arranged in pairs in oppositely inclined lanes in said bank and each pair adapted to connect an object to be supported below said bank to one of said supporting members, and collars fixed on boiler tubes near the lower ends of said suspension members and each adapted to contact and to support laterally a given pair of such members. 80 85 90
